A. L. Gardner
HIS ATTORNEY

UNITED STATES PATENT OFFICE.

JOHN HAYS HAMMOND, JR., OF GLOUCESTER, MASSACHUSETTS.

AUTOMATIC ANTENNA SYSTEM.

Application filed July 9, 1920, Serial No. 395,018. Renewed August 23, 1924.

To all whom it may concern:

Be it known that I, JOHN HAYS HAMMOND, Jr., a citizen of the United States, and a resident of Gloucester, county of Essex, State of Massachusetts, have invented certain new and useful Improvements in Automatic Antenna Systems, of which the following is a specification.

Some of the objects of the present invention are to provide means for maintaining a wireless receiving apparatus in a receptive condition after an antenna to which it is responsive has been grounded by accident or shell fire; to provide means for automatically substituting an operative antenna for an antenna which has been rendered inoperative by grounding; to provide a receiving apparatus having a plurality of antennae one of which is normally operative for receiving purposes and the remaining antennae inoperative, and means for automatically substituting for and rendering operative one of the remaining antennae in case the operative antenna becomes grounded; to provide means for automatically substituting a sound wave responsive means for an antenna responsive means in case the antenna means is rendered inoperative; and to provide other improvements as will hereinafter appear.

In the accompanying drawings, Fig. 1 represents diagrammatically a wireless receiving system embodying one form of the present invention; and Fig. 2 represents diagrammatically another form of the invention.

Referring to Fig. 1 of the drawings, a receiving apparatus 10 of any well known form, responsive to impulses of radiant energy, is graphically represented and arranged to control a desired mechanism 11 such as the steering control of a torpedo, vessel or other marine body. This mechanism 11 is also arranged to be independently controlled by a receiving apparatus 12 of any well known form responsive to sound waves, the apparatus 12 being operatively connected to a receiving diaphragm 13, here shown as located in the body of a trailer 14, though it may be located at any suitable place on the torpedo or vessel itself.

For operating the receiving apparatus 10,

it is included in a tuned circuit 15 having a secondary coil 16 inductively coupled to a primary coil 17 which forms part of an open aerial circuit grounded at 18 and including a battery 20 shunted by a condenser 21 and a conductor 22 connected to a terminal 23.

For the purpose of receiving transmitted radiant energy signals a plurality of antennae are employed, in the present illustration three are shown, 24, 25 and 26, supported respectively at different locations on the superstructure of a marine body 27 and so arranged and connected that but one at a time is responsive to transmitted signals. In the preferred form the antenna 24 is normally responsive and is connected by a lead 30 through suitable deck insulators to one side of a tuning coil 31, the other side of which is connected by a conductor 32 to a condenser 33 and from the condenser 33 to a fixed terminal 34 located in relatively close proximity to the terminal 23. The two terminals 23 and 34 are normally bridged by a movable conducting arm 35 which is pivoted to the terminal 23. A spring 36 is connected at one end to the arm 35 and at the other end to a fixed base 37, the arrangement being such that the spring 36 is in tension when the arm 35 is in its normal position bridging the terminals 23 and 34. An insulating strip 40 subdivides the arm 35 so that it cannot ground through the spring 36 and a like insulation 41 electrically separates the terminal 34 from the base 37 upon which it is mounted. The arm 35 is held in its normal position by a pivoted locking armature 42 which is notched at one end to receive the end of the arm 35 and at its other end is connected by a spring 43 with a fixed part in a manner to retain the arm 35 in its bridging position.

The armature 42 is arranged to be actuated by a magnet 44 which is included in a shunt circuit 45 around the condenser 33 and when energized causes the armature 42 to release the arm 35. In the path of movement of the arm 35 there is a fixed terminal 46 insulated from the base 37 and connected by a conductor 47 with a terminal 48.

The antenna 25 is connected by a lead 50 through suitable deck insulators to one side of a tuning coil 51, the other side of which

is connected by a conductor 52 to a condenser 53 and from the condenser 53 to a fixed terminal 54 located in relatively close proximity to the terminal 48. The general operation and arrangement of the parts is the same as that described in connection with the antenna 24 and therefore detail description is unnecessary, the parts being identified as follows: pivoted conducting arm 55, spring 56, base 57, insulation 60 and 61, pivoted locking armature 62, spring 63, magnet 64, shunt circuit 65, and fixed terminal 66 connected by a conductor 67 with a terminal 68.

15 The antenna 26 is connected by a lead 70 through suitable deck insulators to one side of a tuning coil 71, the other side of which is connected by a conductor 72 to a condenser 73, and from the condenser 73 to a fixed terminal 74 located in close proximity to the terminal 68. The general operation and arrangement of the parts is the same as that heretofore described, and they may be identified as follows: pivoted conducting arm 75, spring 76, base 77, insulation 80 and 81, pivoted locking armature 82, spring 83, magnet 84, shunt circuit 85, and two fixed terminals 86 and 87 connected respectively by conducting leads 90 and 91 to the radiosonic receiving apparatus 12 and sound wave receiver 13. Normally the terminals 68 and 74 are bridged by the arm 75, thus leaving the radiosonic circuit broken at the terminals 86 and 87.

30 In the operation of the form of the invention shown in Fig. 1, the antenna 24 is normally connected to the ground 18 because of the bridging position of the arm 35 and the incoming signals will be received by the circuit 14 to actuate the steering control in the required manner. If the vessel is under fire and a shell should cause the antenna 24 to be grounded, or if for any other reason the antenna 24 becomes grounded, then a 45 circuit will be closed from the antenna 24 to the ground 18 including the battery 20, arm 35, terminal 34, magnet winding 44, to the coil 31 and the lead 30 back to the antenna 24. This energizes the magnet 44 and shifts the armature 42 so that the arm 35 is released and moves, under the influence of the spring 36, to a position bridging the contacts 23 and 46, thus breaking the circuit of the antenna 24 and closing the circuit 50 from the antenna 25 to the ground 18. The last circuit includes lead 50, tuning coil 51, condenser 53, terminal 54, arm 55, terminal 48, conductor 47, terminal 46, arm 35, terminal 23, conductor 22, condenser 21 and transformer coil 31. Any incoming signals will therefore be received by transformer coils 17 and 16 and will operate the receiving apparatus 10 as described.

55 In case the substituted antenna 25 should become grounded, it will close the circuit to the ground 18 through the battery 20, arm 35, terminal 46, arm 55, terminal 54, magnet winding 64, tuning coil 51 and lead 50 to the antenna 25, thereby energizing the magnet 64 and causing the armature 62 to release the arm 55 which moves, under the action of the spring 56, to break the circuit including terminal 54 and bridges the terminals 48 and 66. This connects the antenna 26 with the ground 18 through the lead 70, tuning coil 71, condenser 73, terminal 74, arm 75, terminal 68, conductor 76, terminal 55, arm 55, conductor 47, terminal 46, arm 35, terminal 23, and condensers 21 to transformer coil 17. Any incoming signals will therefore be received by the coils 17 and 16 and operate the receiving apparatus 10 to control the steering as desired.

60 In case the last substituted antenna 26 should become grounded, a circuit will be closed to the ground through the battery 20 by way of the three arms 35, 55 and 75, through the winding of magnet 84, tuning coil 71 and lead 70. This will energize the magnet 84 to draw its armature 82 in a direction to release the arm 75, which is then moved by the spring 76 to break the antenna circuit at the terminals 68 and 74 and bridge the terminals 86 and 87 to close the circuit including the radiosonic receiving diaphragm 13 and the receiving apparatus 12 by which the steering mechanism is now controlled in response to sound waves.

65 Referring to Fig. 2 of the drawings another form of the invention is represented diagrammatically wherein the conducting leads 32, 52 and 72 from the respective tuning coils 31, 51 and 71 of the antennas 24, 25 and 26 are submerged respectively in conducting material such as mercury 92 contained in suitable receptacles 93, 94 and 95 made of insulating material. The receptacle 93 is closed at the bottom by a conducting plug 96 of fusible material which is 100 electrically bonded to the conductor 22 and leads to the battery 20 and shunt circuit of condenser 21, the receiving circuits being completed as described in connection with Fig. 1. The receptacle 93 is suitably supported within a container 97 having a pocket 98 formed in the bottom portion, through the walls of which two terminals 100 and 101 are led, the former having a conductor 102 connected to the conductor 22. The receptacles 94 and 95 are similarly constructed being respectively provided with fusible conducting plugs 103 and 104, containers 105 and 106 having pockets 107 and 108, the pocket 107 having two terminals 110 and 111 and the pocket 108 having two terminals 112 and 113. The terminal 101 is connected by a conductor 114 to the plug 103 and has a branch 115 connected to the terminal 110. The terminal 116

111 is connected by a conductor 116 to the fuse plug 104. The terminal 112 is connected to the conductor 90 previously described as leading to the radiosonic receiving apparatus 12, and the terminal 113 is connected to the conductor 91 leading to the receiving sound wave device 13.

The general operation of this form of the invention is similar to that described for Fig. 1, the antenna 24 being connected to the ground 18 through the tuning coil 31, the mercury in the receptacle 93, fusible plug 96, wire 22 and condenser 21 to the primary coil 17. Signals are thus receivable by the antenna 24 to operate the steering mechanism 11 as previously explained.

If the antenna 24 becomes grounded, the battery 20 is short circuited through the fusible plug 96 which melts and allows the mercury 92 or other liquid conductor in the receptacle 93 to run into the pocket 98 of the container 97. This breaks the circuit from the antenna 24 and closes a circuit through the terminals 100 and 101 whereby the antenna 25 is rendered operative by connection with the ground 18 to receive signals for controlling the steering mechanism.

In case the antenna 25 becomes grounded, the battery 20 will be short circuited through the fusible plug 103 which melts, allowing the mercury to run into the pocket 107 of the container 105, thus connecting the antenna 26 with the ground 18 by way of terminals 110 and 111, so that incoming signals will operate the steering mechanism 11.

Should the antenna 26 become grounded, the battery 20 will be short circuited through the fusible plug 104 which melts and allows the mercury to run into the pocket 108 of the container 106, thus breaking the antenna circuit and closing terminals 112 and 113 to complete a circuit by way of conductors 90 and 91 to bring the radiosonic or sound wave receiving apparatus into commission.

Having thus described my invention, I claim:

1. In a wireless receiving system, a plurality of antennæ, a receiving apparatus responsive to all of said antennæ one at a time, and means for automatically connecting one antenna to said receiving apparatus in place of another antenna.

2. In a wireless receiving system, a plurality of antennæ, a receiving apparatus responsive to all of said antennæ one at a time, means normally connecting one antenna to said receiving apparatus to receive signals, and means rendered operative by the grounding of said connected antenna for connecting another of said antennæ to said receiving apparatus.

3. In a wireless receiving system, a plurality of antennæ a receiving apparatus re-

sponsive to all of said antennæ one at a time, and means for successively connecting an operative antenna to said receiving apparatus as successive connected antennæ are rendered inoperative.

70

4. In a wireless receiving system, a receiving apparatus, a plurality of antennæ, one of said antennæ being operatively connected to said receiving apparatus and the remaining antennæ disconnected from said receiving apparatus, and means rendered operative by said connected antenna becoming grounded to operatively connect one of the remaining antennæ with said receiving circuit.

75

5. In a wireless receiving system, a receiving apparatus, an antenna operatively connected to said receiving apparatus, a compression wave receiving apparatus, a compression wave responsive device, and means rendered operative by said antenna becoming grounded to operatively connect said compression wave responsive device to said compression wave receiving apparatus.

80

6. In a wireless receiving system, a plurality of antennæ, a receiving apparatus responsive to all of said antennæ one at a time, and means including an automatically operated switch for connecting one antenna to said receiving apparatus in place of another antenna.

85

7. In a wireless receiving system, a plurality of antennæ, a receiving apparatus responsive to all of said antennæ one at a time, means normally connecting one antenna to said receiving apparatus to receive signals, and magnet controlled means rendered operative by the grounding of said connected antenna for connecting another of said antennæ to said receiving apparatus.

90

8. In a wireless receiving system, a plurality of antennæ, a receiving apparatus responsive to all of said antennæ one at a time, and means including a plurality of separately operative automatic switches for successively connecting an operative antenna to said receiving apparatus as successive connected antennæ are rendered inoperative.

95

9. In a wireless receiving system, a receiving apparatus, an antenna connected to said receiving apparatus, a compression wave receiving apparatus, a compression wave responsive device, and means including a magnet controlled switch for automatically connecting said compression wave responsive device to said compression wave receiving apparatus when said antenna becomes grounded.

100

10. In a system for the radio dynamic control of a movable body at a distance, a plurality of means positioned on said body and exposed to radiant energy oscillations, control apparatus common to said plurality of means, and automatic means for interconnecting one of said first mentioned means.

105

110

115

120

125

- to said control apparatus operable upon the disabling of said first named means to change the actions of said control apparatus to a different one of said first named means.
- 5 11. In a system of radio dynamic control of a movable body, a plurality of antennæ positioned on said body, control apparatus normally operatively connected with a single one of said antennæ, and automatic means operable upon the disabling of said antenna to connect the control apparatus to another one of said antennæ.
- 10 12. In a system of distant control by radiant energy, a plurality of antennæ for the reception of radiant energy, control apparatus constructed to be responsive to radiant energy received by any one of said antennæ and a series circuit including contacts for each of said antennæ whereby the control apparatus is connected to only one of said antennæ and including mechanism automatically operated by the disabling of an antenna to disconnect said antenna from said series circuit.
- 15 13. In a system of distant control by radiant energy, a plurality of antennæ for the reception of radiant energy, control apparatus constructed to be responsive to radiant energy received by any one of said antennæ and a series circuit including contacts for each of said antennæ whereby the control apparatus is connected to only one of said antennæ and including a source of energy for actuating said automatically operated mechanism.
- 20 14. In a system of distant control by radiant energy, a plurality of antennæ for the reception of radiant energy, control apparatus constructed to be responsive to radiant energy received by any one of said antennæ and a series circuit including contacts for each of said antennæ whereby the control apparatus is connected to only one of said antennæ and including a source of energy for actuating said automatically operated mechanism, and a shunt path for radio currents bridging said source of energy.
- 25 15. In a system of teledynamic control, a receiving circuit comprising a single detecting means for detecting radiant energy, a plurality of antennæ interposed to the action of radiant oscillations in the ether and a series circuit whereby said detecting means is automatically connected only to an operative antenna.
- 30 16. In a system of radio dynamic control, of a movable body, a plurality of antennæ positioned on said body, control apparatus normally operatively connected with a single one of said antennæ, means associated with each of said antennæ arranged to be inactive during the normal operation of the system and automatically actuated when the respective antenna becomes grounded, and a source of energy common to said antennæ for actuating said normally inactive means.
- 35 17. In a system of radio dynamic control, of a movable body, a plurality of antennæ positioned on said body, control apparatus normally operatively connected with a single one of said antennæ, means associated with each of said antennæ arranged to be inactive during the normal operation of the system and automatically actuated when the respective antenna becomes grounded, and a grounded source of energy common to said antennæ for actuating said normally inactive means.
- 40 18. In a system of radio dynamic control, of a movable body, a plurality of antennæ positioned on said body, control apparatus normally operatively connected with a single one of said antennæ arranged to be inactive during the normal operation of the system and automatically actuated when the respective antenna becomes grounded, a grounded source of energy common to said antennæ for actuating said normally inactive means, and a shunt path for currents of radio frequency abridging said normally inactive means.
- 45 19. In a wireless receiving system, a plurality of antennæ, a receiving apparatus responsive to all of said antennæ one at a time and means including an electro-magnetic element for successively connecting an operative antenna to said receiving apparatus as successively connected antennæ are rendered inoperative.
- 50 20. In a wireless receiving system, a receiving apparatus, a plurality of antennæ, one of said antennæ being operatively connected to said receiving apparatus, the remaining antennæ normally remaining disconnected from said receiving apparatus and means including an electro-magnetic element rendered operative upon said connected antenna becoming grounded for operatively connecting one of the other of said antenna with said receiving apparatus.
- 55 21. In a wireless receiving system, a receiving apparatus, a plurality of antennæ, one of said antennæ being operatively connected to said receiving apparatus, the remaining antennæ normally remaining disconnected from said receiving apparatus and means including an electro-magnetic element rendered operative upon said connected antenna becoming grounded for operatively connecting a successive one of said antennæ with said receiving apparatus.
- 60 22. In a wireless receiving system, a receiving apparatus, an antenna operatively connected to said receiving apparatus, a compressional wave receiving apparatus, a compressional wave responsive device, and means rendered operative by said antenna becoming grounded to operatively connect
- 65 70 75 80 85 90 95 100 105 110 115 120 125 130

said compressional wave responsive device to said compressional wave receiving apparatus.

23. In a wireless receiving system, a receiving apparatus, an antenna operatively connected to said receiving apparatus, a compressional wave receiving apparatus, a compressional wave responsive device and means including an electro-magnetic ele-

ment rendered operative by said antennæ 10 becoming grounded to operatively connect said compressional wave responsive device to said compressional wave receiving apparatus.

Signed at Gloucester, county of Essex, 15 State of Massachusetts, the 2nd day of July, 1920.

JOHN HAYS HAMMOND, JR.
